UNITED STATES PATENT OFFICE

ANDREW R. RIDDERSTROM, OF NAHANT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

FEEDING MECHANISM

Original application filed June 24, 1921, Serial No. 480,177. Divided and this application filed October 18, 1922. Serial No. 595,545.

The present invention relates more particularly to feeding mechanisms. The present application is a division of application Serial No. 480,177, filed June 24, 1921, which matured into Letters Patent No. 1,740,409, December 17, 1929.

In finishing the edges of boot and shoe uppers, it is usual to fold the margin of the upper over upon itself, or to fold over upon the margin a binding strip that has previously been sewed to the upper. This folding operation may be performed in a folding machine, in which the upper is advanced by step-by-step feed mechanisms to the folding instrumentalities. In the interest of economy, such folding machines should be operated at high speed. It is easy enough to operate a properly designed folding machine at high speed when folding along straight margins of the upper. Difficulties occur, however, at the curved portions, particularly those portions that are very sharply curved. At such portions, the stock must be fed through the machine either at a lower speed or by shorter feed strokes.

An object of the present invention, therefore, is to provide, in a machine having a feed mechanism, an improved, automatically-acting mechanism, for varying the feed strokes. The range of the feed strokes may be varied automatically from zero to a maximum. The zero or substantially zero range is particularly valuable at sharp, convex curves, for the stock is not then fed forward at all,—or is fed but very little,—but is simply turned in its plane by the operator while the other operating instrumentalities perform the folding.

With this and other objects in view, the invention consists of the improved machine, a preferred embodiment of which is hereinafter described, illustrated in the accompanying drawings, and defined in the appended claims.

In the drawings, Fig. 1 is a view in elevation, partly in longitudinal section, upon a reduced scale, of a machine constructed according to a preferred embodiment of the present invention; Fig. 2 is a perspective view illustrating the folding action at a sharp convex curve; Fig. 3 is a perspective view, with

parts in section and broken away, of the main driving shaft and its speed-and-feed-controlling mechanisms; Figs. 4, 5 and 6 are sections taken substantially upon the lines 4—4, 5—5 and 6—6, respectively, of Fig. 3, looking in the direction of the arrows; Fig. 7 is a transverse vertical section taken substantially upon the line 7—7 of Fig. 8, looking in the direction of the arrows; and Fig. 8 is a longitudinal vertical section of the forward part of the machine.

The invention is illustrated in the accompanying drawings in connection with a machine for folding a binding strip 2, Fig. 2, around the edge 4 of a sheet of leather or other material 6, such as a boot or shoe upper. An edge 8 of the binding strip is stitched at 12 to a face 10 of the shoe upper along the edge 4, so that the sheet and the strip extend at an angle to each other from the secured-together edges 4 and 8. It will be understood that the invention is equally applicable to other machines than folding machines.

The shoe upper is initially placed in the machine upon a platform or support 24, with the face 10 of the upper in contact with the support. An end of the free or unsecured edge 26 of the strip 2 is initially moved across and around the secured-together edges 4 and 8 and into the space between an interior side face 28 of a feed point 30 (Figs. 2 and 8) and a plow 32 that stands up integrally from a plate 34. The machine being set into operation, successive portions of the strip 2 near the stitches 12 are intermittently wiped tightly across the secured-together edges 4 and 8, or away from the stitches 12, by the combined action of a wiper 38 (Fig. 2) and a retainer 246 that presses down heavily at this time upon the upper directly opposite to the point of action of the wiper. The successively wiped portions are initially intermittently folded around the secured-together edges 4 and 8 by the plow. The plow-folded portions are then advanced by feeding mechanism comprising the feed point and a cooperating feed block 41 to a combined folder and fold presser 42 (Fig. 2). The feed block 41 is carried integrally with the plow 32.

upon the plate 34. The fold presser 42 folds the plow-folded portions of the strip further and presses them down against the other face 16 of the sheet, as shown in Fig. 2.

5 The feeding mechanism is driven by a driving shaft 66, that is horizontally journaled in bearings of the machine frame. The driving shaft is provided with a hand-and-balance wheel 68, Figs. 1 and 3, having a clutch 10 face 70 that is adapted to be frictionally engaged by a clutch face 72 of a loose driving cone pulley 74. The cone pulley is normally separated from the hand-and-balance wheel by a spring 76, but may be actuated 15 toward the latter, to effect frictional engagement of the clutch faces, by a bell-crank lever 78 pivoted at 80 and operable through a treadle or other manually controlled device (not shown) that is connected to the bell- 20 crank lever by a link 82. According as the treadle is depressed more or less, the clutch faces will engage more or less firmly, thus providing for varying the speed of rotation of the driving shaft 66. Upon the release of 25 the treadle, the bell-crank lever will be returned to its illustrated, ineffective position by a compression spring 84 mounted upon a rod 86 that is pivotally mounted at its lower end in an abutment 88. The spring 76 will 30 at the same time separate the clutch faces 70 and 72, and a brake 90, that is pivoted at 91 to the frame of the machine, will be acted upon at 193 by an adjustable member 92 that is carried by the bell-crank lever to stop the 35 rotative movement of the hand-and-balance wheel 68 and, therefore, of the driving shaft 66.

The plate 34, that carries the feed block 41 and the plow 32, is mounted upon a holder 40 93 that is secured, as by a set screw, to a rocking support 94. The rocking support is pivotally mounted about a rod 96 that is secured to the frame of the machine by a screw 98. The rocking support 94 is provided with 45 a diagonally disposed cylindrical opening 100, Figs. 7 and 8, within which is slidably mounted a diagonally cylindrical block 102 the upper flat face of which is substantially horizontal, as shown at 104. The angle of 50 inclination of the opening 100 is preferably in the neighborhood of thirty degrees. The cylindrical block 102 is adapted to be actuated by an eccentric or crank pin 106 of the driving shaft 66. The eccentric or crank pin 55 is rotatably mounted in the block 102 and extends through an opening 108 of the rocking support 94. Rotative movement of the shaft 66 will be converted by the eccentric into combined sliding and oscillating or rotative 60 movement of the block 102 and this, in turn, will effect a rocking movement of the rocking support about the rod 96.

The feed point 30 is pivotally mounted at 65 110 upon the rocking support 94 so as to be rocked therewith and with the lower feed

block 41, and is normally maintained in contact with the feed block by a leaf spring 112 one end 114 of which is secured to the frame of the machine, as shown in Fig. 1, and the other end 116, Fig. 8, of which presses down upon the body portion 118 of the feed point. The body portion 118 is slotted, as shown in Fig. 7, and a screw post 120 is adjustably clamped between the side walls of the slot by a screw 122, Fig. 8. The upper face 104 of the block 102 is adapted to engage the post 120, thereby to raise the feed point 30 in opposition to the pressure of the spring 112. The tension of the spring 112 upon the body portion 118 of the feed point may be adjusted by a clamp screw 124, Fig. 1, having a shoulder 126 for engaging the spring. In order to prevent lateral movement of the spring 112, it is mounted in a longitudinal slot 128, Fig. 1, provided in the upper surface 85 of the machine frame.

As the driving shaft 66 is rotated, the rocking support 94 is rocked from right to left and from left to right, as viewed in Fig. 7, imparting an oscillating movement to the lower feed block 41 and the upper feed point 30 which are carried thereby. During the left-to-right movement, the feed point 30 will be separated from the feed block 41 by the action of the cylindrical block 102, which then occupies its upper position. During the right-to-left movement, the block 102 will lie in the lower portions of the cylindrical opening 100, and the feed point will be spring-pressed into engagement with the feed block, which will thus advance to the fold presser the upper clamped therebetween.

During the backward movement of the feed elements and the plow from the fold presser towards the wiper, the feed point first rises from the full-line position to the dotted-line position of Fig. 8. Then, towards the end of the backward movement, it descends again to the full-line position. A separator 143 is provided just in front of the plow to maintain the strip separated from the raw edges 4 and 8.

At sharply curved places in the stock, the machine should be slowed down. This may be effected by pressing the clutch faces 70 and 72, Fig. 1, a little less tightly together by suitable manipulation of the treadle rod 82. According to the present invention, slowing down the speed of the machine automatically reduces the rate of feeding movement, so that curved parts of the material are fed through the machine not only at less speed, but by shorter feed strokes, as well. This desired result is brought about, in the illustrative machine, by automatically adjusting the eccentricity of the eccentric 106 upon the end of the shaft 66, in accordance with the value of the speed of rotation of the shaft 66, causing the rocking support 94 to be rocked, through greater or less amplitudes of rocking 115 120 125 130

movement, as the case may be. The rocking support may, indeed, be maintained absolutely stationary, preventing any feed movement at all, which is very desirable 5 when very sharp concave or convex portions of the stock are encountered. At such places the wiper, the fold presser and the other operating instrumentalities continue to operate while no feeding at all takes place; the 10 operator simply turning the stock in its plane to permit successive portions of the margin to become successively folded. The operation will be understood more particularly from Fig. 2, where the edge 26 of the 15 binding strip is shown crowded a little, by minute stages, at 448. The crowding is of so minute a character, that, for practical purposes, the edge fold is perfectly smooth, unmarred by any wrinkles or bunching whatsoever. Feed control of this character is believed to be produced herein for the first 20 time, and is considered to be of far greater application than to binding-strip-folding machines in particular, or shoe machines in 25 general. The specific construction employed will now be described.

The driving shaft 66 is shown more particularly in Fig. 3, provided with a longitudinal eccentric bearing 450 for a second shaft 30 452 upon the forward end 454 of which the eccentric or crank stem 106 is carried. The bearing 450 may be produced by longitudinally drilling through the shaft 66; or, preferably, the shaft 66 may be made hollow to 35 start with and bushings 456 plugged into its ends. The bushings are eccentrically bored to provide the bearing 450. The space 458, between the bushings, may be utilized as an oil chamber. According to the actual construction illustrated, but one bushing 456 is employed, at the rear end of the shaft, the forward end being shown solid. The forward wall of the oil chamber 458 is indicated, in 40 dotted lines, at 460. In whatever manner 45 the structure is manufactured, it will be clear that, by rotatably adjusting the shaft 452 within the bearing 450, the eccentric or crank stem 106 may be made to assume different eccentric positions upon the forward end of the 50 shaft 66. According as the crank stem is adjusted nearer to or farther from the center of the shaft, the feed steps will be shortened or lengthened. If the crank stem is caused to assume a position exactly central of the shaft, 55 as illustrated in Fig. 2, it will remain exactly central throughout the rotation of the shaft, and the shaft will continue to rotate without rocking the rocking support 94; and the feed elements will therefore remain at rest.

60 The length of the feed strokes is automatically varied in accordance with the variation in speed by connecting the shaft 452, through the medium of segmental gears 462 and 464, to governor weights 466. The weights 466 and the segmental gears 462 and 464 are in-

tegral with arms 468 that are pivoted at 470 to the hand-and-balance wheel 68. As the machine speeds up, the governor weights are centrifugally forced outward pivotally about the pivotal points 470, causing the gears 464 and 462 to rotate the shaft 452 within its bearings 450. As the machine slows down, very stiff springs 472, each attached at one end 474 to the arms 468, and at the other end 476 to a stationary part of the balance 70 wheel 68, draw the governor weights back toward normal position, correspondingly rotatably adjusting the shaft 452. Any intermediate rate of feed between maximum and minimum values may be obtained by speeding the machine up more or less, as desired, the variable centrifugal force acting upon the governor weights 466 at different speeds being always balanced by the variable tension on the springs 472 corresponding to those 75 speeds.

To increase or decrease the normal tension on the springs, the ends 476 are secured, not directly to the hand-and-balance wheel, but to diametrically opposed points of a spring collar 478 that is split at 480 to facilitate its mounting within an annular groove 482 of the hand-and-balance wheel 68. The collar 478 is provided with gear teeth 484 that mesh with the teeth of a pinion 486 that is secured, as by means of a pin 488, to a plunger 490. The plunger 490 is mounted within a recess 492 in the web 494 of the hand-and-balance wheel 68 and is maintained in the outward 80 position illustrated in Fig. 5 by a coil compression spring 496. The pinion 486 is provided with ratchet teeth 498 that engage ratchet teeth 500 upon the inner face of a block 502 that is set in position within a recess 504 upon the periphery of the hand-and-balance wheel. The plunger 490 extends through an opening 506 of the block 502 and its head is slotted at 508 to receive a screw driver. When it is desired to adjust the normal tension of the springs 472, a screw driver is inserted in the slot 508, the plunger 490 is forced inward by pressing in on the screw driver, in opposition to the force of the spring 496, thereby disengaging the ratchet teeth 95 498 from the ratchet teeth 500. The screw driver is then turned to rotate the pinion 486, in one direction, or the springs 472 are permitted to effect rotation of the pinion in the opposite direction. Rotation of the pinion causes rotation of the split collar 478 in one or the other direction. Releasing the screw driver results in the plunger becoming spring-forced back into place, to cause the ratchet teeth 498 and 500 to engage once more, locking the split collar in adjusted position.

100 The limits of the rate of feed may be adjusted by slidably adjustable stops 510 and 512 (Fig. 3), the former adapted to be engaged by one of the governor weights 466 to 105 limit the outward movement of the governor, 110

and the latter by the other governor weight 466 to limit its inward movement. By adjusting the stop 510, the maximum rate of feed may be adjusted; by adjusting the stop 512, the minimum rate of feed may be controlled within any desired limits between zero and any other desired minimum value. The stops 510 and 512 may be adjusted by rotating screw-threaded rods 514 that are threaded through screw-threaded openings 516 of the stops. The screw-threaded rods 514 are mounted in bearings 518 and 520. Collars 521 prevent longitudinal movement of the rods 514.

15 As will be understood from Figs. 1 and 3, the gear 462 is held against the bushing 456 by a button 522 that is screwed into the forward end of a short shaft 524 mounted in the bearing collar 526. For purposes of convenience in assembly, the bushing 456 and the shaft 524 are provided with annular flanges 528 and 530, respectively, that are secured to each other and to the hand-and-balance wheel by screws 532.

25 Although the invention has been described above in connection with a special machine disclosed in the above-identified Letters Patent, it will be understood that this is for illustrative purposes only, and that the invention is of broader scope, unlimited except insofar as limitation may be specifically imposed in the appended claims.

What is claimed as new is:

1. A machine of the class described having, in combination, a driving shaft having an eccentric, feeding means connected to the eccentric so as to be driven thereby, means for driving the shaft at varying speeds, at will, and a governor automatically controlled 35 in accordance with the speed of the driving shaft for varying the position of the eccentric upon the shaft to vary the rate of feed of the feeding means.

2. A machine of the class described having, 45 in combination, a rocking support having a diagonally disposed opening, a diagonally disposed block slidably mounted in the opening, a driving shaft having an eccentrically disposed opening, a shaft mounted in the shaft opening having an eccentric connected with the block for slidably driving the block in the diagonally disposed opening, and means controlled in accordance with the speed of 50 operation of the driving shaft for adjusting the position of the second-named shaft within the opening to vary the driving action of the eccentric.

3. A machine of the class described having, 60 in combination, a driving shaft having a longitudinal eccentric opening constituting an oil chamber, a shaft longitudinally mounted in the opening having an eccentric, and a governor controlled in accordance with the 65 speed of the driving shaft having means for

adjusting the position of the second-named shaft within the opening.

4. A machine of the class described having, in combination, a rocking support having a diagonally disposed opening, a diagonally disposed block slidably mounted in the opening, a feed member fixed to the support, a cooperating feed member biased toward the first-named feed member and movable away from the first-named feed member by the block, a driving member having an eccentric for simultaneously actuating the block in the opening and rocking the support, means for actuating the driving member at variable speeds, and means controlled 75 in accordance with the speed of actuation of the driving member for varying the degree of rocking movement of the support.

In testimony whereof, I have hereunto subscribed my name this 16th day of October, 85 1922.

ANDREW R. RIDDERSTROM.
